LIQUID ATOMIZERS

Calvin D. MacCracken and James M. Relph, Tenafly, N.J., assignors to Jet-Heet, Inc., Englewood, N.J., a corporation of New York

Application January 14, 1957, Serial No. 633,929

10 Claims. (Cl. 239—446)

This invention relates in general to liquid atomizers and particularly to a new and useful atomizer in which the output of atomized liquid is controlled by regulating the amount of liquid supplied to a plurality of exit orifices arranged at the discharge of the atomizer. While not limited thereto, this invention finds particular application in and will be described with special reference to atomizers for liquid fuel burners.

There are numerous instances such as in marine and industrial burner applications where it is highly desirable to have a mechanical fuel atomizer operable at constant fuel supply pressure and with output variable readily over a fuel flow volume range from a maximum to a minimum flow ratio of as much as, or more than, 40 to 1 without appreciable change in the atomizer spray angle or conditions of atomization. Previously it was necessary to either change the pressure of the fuel supply or in cases where the atomizer has a return flow line to vary the pressure in the return line, or to disconnect the orifice plate from the remaining portions of the atomizer and replace it with one of different size in order to change the output of the atomizer.

In accordance with this invention wide variations of fuel output volume with excellent conditions of atomization may be achieved without varying the fuel supply or return pressures or the sizes of any of the atomizer parts. A preferred embodiment of the invention includes an atomizer having a plurality of circumferentially spaced symmetrically arranged discharge orifices which are supplied with liquid to be atomized from a plurality of internal passages located in the atomizer body and having inlet ports at spaced locations along the atomizer body bore which are sequentially opened to the liquid supply by an axially slideable internal valve. The valve may be moved to any position to uncover one or all of the passages and to vary the atomizer liquid outlet capacity in accordance with the number of passages feeding liquid to the orifices. Liquid is delivered to each of these orifices in a high velocity vortex flow which is established in conical swirl chambers communicating with the orifices and the internal passages. Thus by selectively opening and closing the individual passages by means of the axially slideable valve, it is possible to obtain a maximum flow rate volume to a minimum flow rate volume ratio of as much as 40 to 1.

An atomizer constructed in accordance with this invention may be readily adaptable for any ordinary clean liquid atomization such as water, or fuel atomization as in burner applications. It has been found that for burner use the fuel will atomize with substantially the same spray cone angle and flame conditions when one, two or more of the orifices is supplied with and is atomizing fuel. When the second orifice is cut in after the fuel from the first has been fired, the arrangement of discharge is such that the spray angles and flame pattern will blend into one big spray cone rather than form two individual cones. The atomizer has little appreciable change in atomizer

2

spray angle or flame burning conditions over its wide range of fuel atomizing output.

Accordingly it is an object of this invention to provide an atomizer which is supplied with liquid at constant pressure and is capable of atomizing the fuel over a wide range of atomized liquid output.

A further object is to provide an atomizer which is supplied with liquid at a constant pressure and has a plurality of discharge orifices in communication with separate liquid delivery passages, and includes a valving element which is movable gradually to effect communication of each passage in succession with the liquid to be atomized.

A further object is to provide a liquid atomizer of the character described which is simple in design, rugged in construction and economical to manufacture.

For a better understanding of the invention, its operating advantages, and specific objects attained by its use, reference should be had to the accompanying drawings and descriptive matter in which there is illustrated and described a preferred embodiment of the invention.

In the drawings:

Figure 1 is a side elevation, partly in section of an atomizer gun embodying the invention;

Figure 2 is an enlarged sectional view of the atomizer portion of the gun assembly of Figure 1;

Figure 3 is a sectional view of the distributor portion of the atomizer taken on the line 3—3 of Figure 2;

Figure 4 is an enlarged end elevation of the rear face of the sprayer plate portion of the atomizer;

Figure 5 is a sectional view of the sprayer plate taken on the line 5—5 of Figure 4;

Figure 6 is a curve showing the variation of atomized liquid output obtainable with an atomizer embodying the invention;

Figure 7 is a schematic development of the arrangement of the internal passage inlets of the distributor barrel of another embodiment of the invention and showing the manner in which the axially movable valve uncovers each inlet in succession as it is moved towards the forward or discharge end of the atomizer; and

Figure 8 is a sectional view taken on the line 8—8 of Figure 7.

Referring to the drawings in particular, the invention as embodied therein includes an atomizer gun generally indicated 10. In the usual case this gun assembly will be incorporated in a burner to discharge atomized fuel into the combustion chamber of a furnace, although the burner assembly and furnace have been omitted from the drawing as unnecessary to an understanding of the invention.

The atomizer gun 10 includes an elbow member 12 having an inlet conduit 14 through which a liquid fuel is supplied under constant pressure from any suitable source (not shown). The forward or discharge end of the elbow member 12 is internally threaded to receive a tubular barrel or sleeve 16 which, in turn, is externally threaded at its forward end as at 17 (see Figure 2) to receive an atomizer assembly 18. Liquid is supplied under pressure through the inlet 14 and through the interiors of the elbow member 12 and the barrel 16 to the atomizer assembly 18 under the control of a valve element generally designated 20.

The valve element 20 is affixed to the forward end of a long shaft 22 which extends from the atomizer assembly 18 backwardly through a bearing sleeve 24 threaded onto the rear end of the elbow member 12. A suitable packing 25 prevents the escape of liquid from the inside of the elbow member 12. The shaft 22 extends rearwardly beyond the edge of the elbow member 12 and is enclosed by a tubular housing 26 which is fastened to the elbow member 12 as by screws 27. The housing 26 is closed

at its opposite end by an end plug 28 which is hollowed in the center in order to accommodate and support a spindle piece 30. The spindle piece 30 is provided with an elongated portion which extends rearwardly beyond the edge of the plug 28. A handle 32 is attached to a nut 34 which is fitted over the elongated portion of the spindle piece 30 and is affixed thereto as by a set screw 36. The nut 34 is provided with an indicator pointer 38 which is positioned adjacent an indicator dial 40 having a calibrated scale arranged to give a relative indication of the fuel output of the atomizer from settings of 0° to 360°.

The spindle piece 30 extends inwardly beyond the plug 28 and has a hollowed internal portion in which is located a plurality of radially projecting spline keys 42 which normally ride in the grooves of a spline 44 affixed to the end of the shaft 22. The spline keys 42 permit independent axial movement of the shaft 22 relative to the spindle piece 30 but rotation of the handle 32 will cause rotation of the spindle piece 30 and hence rotation of the shaft 22 through the medium of the spline keys 42 and the spline 44.

A worm gear 46 is affixed to the shaft 22 and normally engages a plurality of bolt-like teeth 48 which are affixed to and protrude inwardly from the wall of the housing 26. Rotation of the shaft 22 by means of the handle 32 effects the axial movement of the shaft as the worm gear affixed thereto is advanced by engagement with the bolt-like teeth 48.

Referring to Figure 2, the atomizer assembly 18 includes a housing piece or distributor 50 which is threaded onto the barrel 16. The distributor 50 is hollow, having a cylindrical bore defining an internal liquid delivery chamber 52 which is closed at the forward end but which is open at the opposite end to accommodate the valve element 20, the latter being capable of reciprocating axially therein. The walls of the distributor are beveled as at 54 to permit unhindered flow of liquid from the barrel 16 into the distributor when not blocked by the valve element 20. The valve element 20 has a tight sliding fit in the distributor liquid supply chamber 52 with a substantially liquid tight sliding seal being provided by a packing ring 56 affixed to the shaft 22 and held thereon against the valving element 20 as by a nut 57. A sprayer plate 58 is positioned on the discharge end of the distributor 50 and is held in place thereon by a cap nut 60 threaded onto the distributor 50 as at 17a and aligned thereon by suitable pin and slot connections as at 62.

In accordance with the invention the sprayer plate 58 is provided with a plurality of discharge orifices 64 which in this instance are symmetrically arranged at circumferentially spaced locations. In the present instance there are six orifices arranged with their discharge axes parallel and closely spaced to effect atomization into a single spray cone. A number more or less than six could be provided without departing from the principles of this invention. However, the arrangement in this case will give a fuel output range of from approximately 40 to one. The orifices 64 may all be of the same size or may be of varying sizes in order to achieve fine adjustments in fuel output. In the present case, four orifices are of equal diameter and two others are of different diameters, giving three sizes of orifices in all. It has been found desirable to make the diameters and the depths of the orifices which are used at low fuel rates smaller than the corresponding dimensions of those orifices which come into play at higher flow rates.

Each of the orifices 64 communicate with cylindrical swirl chambers 66 through intermediate frustro-conical chambers 68 which are drilled in the sprayer plate 58 (see Figures 4 and 5). Each swirl chamber 66 is supplied with liquid from three substantially rectangular tangentially directed slots 70a, 70b and 70c of varying sizes. The larger two of the slots 70a and 70b communicate with a longitudinal passage 72a and a branch

passage 72b perpendicular thereto drilled in the distributor 50. The smallest slot 70c communicates with a longitudinal passage 72c also drilled in the distributor 50.

The liquid supply chamber 52 of the distributor 50 is provided with a plurality of ports 74 (which in this instance are of equal diameters) arranged in equally spaced positions along the length of the bore at circumferentially offset locations. The ports 74 are connected by means of short lateral passages 76 to the longitudinal passages 72a and 72c.

The larger two tangential slots 70a and 70b are both supplied with fuel through passages 72a and 72b fed by a single port 74, and the smallest slot 70c alone is supplied with fuel through the passage 72c fed by a single port. Thus when a port 74 is cut in which feeds the passage 72c and the smallest slot 70c, a fuel output of under 50% of the orifice maximum output may be obtained. However, if a port feeding the larger slots 70a and 70b is cut in before the smallest slot-port, the output of the orifice will be as much as 98% capacity. Therefore for more gradual fuel output increase the smallest slot 70c of each orifice is arranged to be cut in before the other two. In this connection it will be appreciated that many variations in fuel output for each orifice 64 may be achieved by changes in the sizes of the tangential slots 70a, b, c and the manner in which they are arranged to cut in.

The following table contains representative dimensions in inches for the various sprayer plate orifices and their associated slots, for a typical installation in which the flow rate was made variable between 0 and 4300 pounds per hour of No. 6 fuel oil:

Orifice Cut-In	Orifice Length	Orifice Diameter	Depth of Slot 70c	Depth of Slots 70a, 70b
First.....	.027	.0465	.0148	.0512
Second.....	.036	.0625	.0243	.0976
Last Four.....	.041	.073	.0404	.1280

In the foregoing case, the slot widths were all .0625", and all of the swirl chambers had a maximum diameter of .281" in a sprayer plate .275" thick; the centers of the discharge orifices being .365" from the center of the sprayer plate.

The operation of the atomizer is as follows: With the valve 20 in a closing position (see Figure 2), the fuel will be confined under pressure in the elbow member 12 and the barrel 16, and will not flow through the liquid supply chamber 52 of the distributor 50 into a port 74. As the handle 32 is rotated, the valve element 20 is moved forward in the chamber 52 and the rear edge thereof passes beyond one of the ports 74 to open it and permit fuel to flow into the port. The first port in line is arranged to communicate with the smallest one of the orifices 64 through its associated small tangential slot 70c and the passage 72c. The orifice size chosen for first operation is the size which will obtain a fuel output of lower than 100 pounds per hour so that very small quantities of fuel may be discharged from the atomizer as it is cut in. Further movement of the valve element 20 is effective to uncover the port feeding the passages 72a and 72b and the slots 70a and 70b of the same orifice 64. Additional movement of the valve element 20 is effective to uncover first the port feeding the small tangential slot 70c and then the port feeding the slots 70a and 70b of each of the other orifices in succession until all of the orifices are discharging fuel.

A curve showing the fuel output obtainable for various rotational positions of the handle 32 is shown in Figure 6. It can be seen that variations in fuel output from below 200 to over 4300 pounds per hour can be obtained with settings from zero to 360° of the handle 32. The variations in the flow rates which are obtained with the atom-

izer of the present invention may occur at handle setting increments which may be made small enough to provide for a gradual ever increasing fuel output. It will be noted in this connection that when the valve element 20 is moved to uncover the ports 74 there is a brief period where a large increase of fuel rate occurs shortly after the port has been opened and then there is a longer period where relatively little or no increase in fuel rate occurs until the next port has been uncovered. This is shown graphically by the dotted lines on the curve of Figure 6. (In this case the ports are fully open at each 30° increment of handle rotation.) By choosing two relatively small sized orifices 64 out of the group of six it is possible to use a combination of atomizers or a single atomizer in such a way that the small orifices will come into play at the times when small increases of fuel rate is desired or for initial cut-in at low burning load requirements.

The embodiment shown in Figure 7 is advantageously used in those instances in which it is desirable or necessary to have very small and even increments of change of fuel output over the operating ranges incurred. For some controls it is preferable to have a smooth curve of flow versus handle position. In order to accomplish this, the valving element 20 is augmented by a trailing valve piece or element 78 which is also affixed to the shaft 22 immediately behind the main valve element 20. The trailing valve element 78 is a flat disc similar to the valving element 20 but provided with a plurality of holes 79 drilled through the piece parallel to the axis of the shaft 22. The trailing element 78 is made to a thickness sufficiently great to throttle the opening of only one of the last opened one of the ports 74, just as the forward valve element 20 moves into position to uncover the next port. Fuel may flow into each port uncovered by the forward valve element through the holes 79 (see dotted line position in Figure 7). With such an arrangement very even and gradual increases of fuel output are obtained with the atomizer.

The provision of a trailing valve element 78 as shown in Figure 7 permits the fast opening of a port 74 by the leading element 20 without a rapid jump in fuel output because the trailing element is simultaneously closing the previously opened port. A gradual opening or "cracking" of the port 74 by the valve element 20 alone would only produce a drip of fuel out the orifice 64 in cases where the orifice is not already being supplied with fuel from another port. This is so because the fuel does not obtain a sufficient velocity to atomize into a spray. However with two valve elements it is possible to avoid "cracking" each port. Each newly cut in port may be opened quite rapidly by the leading element 20 and the output will increase only gradually because the trailing element 78 is simultaneously throttling the previously opened port 74.

The invention provides a compact, easily operable atomizer gun which is capable of atomizing fuel through a plurality of discharge orifices over an output range varying from a maximum to a minimum of more than 40 to 1 depending on atomizer design as to orifice size, valve element size and port size and spacing. Liquid or fuel may be discharged from one or more of the orifices in a uniform atomized spray pattern. The first orifice to come into play forms an atomizing spray pattern which remains unchanged as subsequent orifices come into use. It has been found that fuel discharged from subsequent orifices tends to be picked up and carried by the atomizing spray of the first orifice. Any tendency for any one of the subsequent orifices which come into use to depart from the initially established spray angle is resisted by orifices already functioning.

While a specific embodiment of the invention has been shown and described in detail to illustrate the application of the invention principles, it will be understood that the invention may be embodied otherwise without departing from such principles.

What is claimed is:

1. A liquid atomizer operable at constant liquid supply pressure over a wide output range including a sprayer plate having a plurality of orifices therein each communicating with individual swirl chambers defined therein, said sprayer plate also having a plurality of liquid delivery slots tangentially connected to each of said swirl chambers, conduit means separately connected to each of said liquid delivery slots, a common liquid supply means for said conduit means connected to said conduit means, and valving means separating said supply means from said conduit means and movable to open each of said conduit means to said supply means in succession whereby to supply liquid for discharge through each of the orifices in said sprayer plate in succession.
2. A liquid atomizer operable at constant liquid supply pressure over a wide output range including a sprayer plate having a plurality of orifices therein angularly spaced about a central axis and each communicating with individual swirl chambers defined therein, said sprayer plate also having a plurality of liquid delivery slots tangentially connected to each of said swirl chambers, normally closed conduit means separately connected to the liquid delivery slots of each of said swirl chambers through which to supply liquid under pressure thereto, means to provide a supply of liquid under constant pressure to said conduit means, and means to open each of said conduit means in succession whereby to supply liquid under pressure for discharge through each of the orifices in said sprayer plate in succession.
3. A liquid atomizer as defined in claim 2, including a valving element coupled to said valving means for closing a previously opened conduit means upon the opening of an additional one of said conduit means whereby to obtain a smaller net increase in the total discharge from said atomizer upon the opening of said additional one of said conduit means.
4. A liquid atomizer operable at constant liquid supply pressure over a wide output range including a sprayer plate having a plurality of orifices therein uniformly angularly spaced about a central axis and each communicating with individual swirl chambers defined therein, said sprayer plate also having a plurality of liquid delivery slots tangentially connected to each of said swirl chambers, a distributor element connected to said sprayer plate and having liquid supply passages therein communicating each with at least one of said delivery slots, normally closed means connected to each of said distributor supply passages, and means to open each of said normally closed means and said liquid supply passages in succession whereby to supply liquid under pressure for discharge through each of the orifices in said sprayer plate in succession.
5. In an atomizer gun assembly, a variable flow liquid atomizer comprising an elongated hollow body, means connected to one end of said body having a plurality of discharge orifices, said orifices lying in a common plane with their discharge axes parallel to each other, means within said atomizer adjacent said orifices defining a plurality of swirl chambers communicating one with each said orifice, and each said swirl chamber having a plurality of liquid delivery slots opening tangentially thereinto, said body having a plurality of liquid delivery passages extending longitudinally in the walls thereof, there being a passage in communication with each separate swirl chamber through at least one of said associated swirl chamber delivery slots, said hollow body defining a central bore communicating with said passages through axially and circumferentially displaced radial openings in said walls, a liquid delivery duct communicating with said central bore, and a valving element fitting closely in said central bore to separate said delivery means from said radial openings, said valving element being slidable axially in said bore to bring said open-

ings into communication sequentially with said fluid delivery means.

6. A variable flow liquid atomizer comprising an elongated hollow body, orifice-defining means connecting one end of said body defining a plurality of discharge orifices, said orifices lying in a common plane with their discharge axes parallel to each other, swirl chamber defining means within said atomizer adjacent to said orifice defining means and defining a plurality of swirl chambers communicating one with each said orifice, each said swirl chamber having three liquid delivery slots opening tangentially thereto, said slots being graduated in depth to provide one small slot and two larger slots of equal dimensions for each said chamber, said hollow body having a plurality of liquid delivery passages extending longitudinally in the walls thereof, there being a separate pair of said passages of different diameter in communication with each separate swirl chamber through the associated swirl chamber delivery slots, the smaller of said pair of passages being in communication with said small slot and the larger of said passages being in communication with said larger slots, said hollow body encompassing a central bore communicating with said passages through axially and circumferentially displaced radial openings in said walls, a liquid delivery duct communicating with said central bore at said open end of said body and adapted to be connected to a source of liquid under constant pressure, a valving element fitting closely in said central bore to separate said delivery duct from said radial openings, said valving element being slideable axially in said bore to bring said openings into communication sequentially with said delivery duct.

7. A variable-flow liquid atomizer comprising in combination, a sprayer plate having a plurality of fixed discharge orifices therein spaced uniformly about said plate, means defining a plurality of swirl chambers communicating one with each said orifice, each said swirl chamber having a plurality of spaced liquid delivery slots opening tangentially thereto, a distributor element cooperable with said means defining said swirl chambers for delivering liquid to said slots and comprising a hollow cylindrical member having a plurality of liquid delivery passages extending longitudinally in the walls thereof and terminating in outlet ports in the bore of said distributor element which register one with each of said slots, liquid delivery means communicating with said central bore of said distributor element, and a valving element fitting closely in the central bore of said distributor element and covering said radial openings to separate said delivery means from said radial openings, said valving element being slideable axially in said bore to sequentially uncover said radial openings thereby to bring said openings into communication with said liquid delivery means.

8. A variable-flow liquid atomizer comprising in combination, an elongated hollow body, a sprayer plate at one end of said body, said plate having a plurality of fixed spray orifices therein uniformly angularly spaced about a central axis of said plate, said plate having swirl chambers formed therein one adjacent to each said orifice, each said swirl chamber having a plurality of spaced liquid delivery slots opening tangentially thereto, said hollow body having a plurality of liquid delivery passages extending longitudinally therein and terminating in outlet ports which register and communicate with one of said delivery slots, said body having a central bore therein communicating with said passages through circumferentially and axially displaced radial ports, a liquid delivery duct communicating with said central bore, and a valving element fitting closely in said

70

central bore and covering said radial openings to separate said delivery duct from said ports, said valving element being slideable axially in said bore to sequentially uncover said ports, thereby to bring said ports sequentially into communication with said liquid delivery duct.

9. A liquid atomizer operable at constant liquid supply pressure over a wide range of fuel output including a sprayer plate having a plurality of orifices thereon angularly spaced about a central axis and each communicating with individual swirl chambers defined therein, a hollow distributor defining a central bore connected to said sprayer plate and having liquid supply passages therein communicating one with each of said swirl chambers and said discharge orifices, and having ports extending to the central bore thereof at axially displaced positions therealong, liquid delivery means communicating with said central bore, and a valving element fitting closely in said central bore and preventing communication of said liquid delivery means with the portion of said bore having said liquid supply passage ports defined therein, and means to slide said valving element axially in said bore to sequentially uncover said ports and to bring them into communication with said liquid delivery means for liquid flow therethrough and discharge through its associated orifice.

10. A variable-flow liquid atomizer comprising in combination, a sprayer plate having a plurality of orifices therein, a hollow distributor cooperable with said sprayer plate for delivering liquid thereto and atomizing the liquid, said distributor having a plurality of liquid delivery passages extending longitudinally therein and terminating in outlet ports which communicate one with each of said orifices, said body distributor having a central bore therein communicating with said passages through axially spaced radially extending ports defined therein, fluid delivery means communicating with one end of said central bore, and a valving element including a leading portion and a trailing portion spaced from said leading portion and each fitting closely against the walls of said distributor in the bore thereof, said leading portion normally completely closing the fuel delivery communicating end of said distributor, said trailing portion having a passage therein permitting fluid delivery communication therethrough to the space in said bore between said valve portions, and means to move said valve element axially in said distributor bore, movement of the leading portion thereof being effective first to uncover the nearest one of said ports and thereby bring said port into communication with said fluid delivery means through the passage in said trailing portion, and further movement being effective to begin uncovering the next one of said ports and to bring it into similar communication with said fluid delivery means through the passage in said trailing portion while said trailing portion begins covering the previously uncovered one of said ports, said valving element being slideable axially in said bore thereafter to sequentially uncover all of said radial openings in succession as the previously uncovered one is being covered whereby to bring each into communication sequentially with said fluid delivery means.
